THEFT RESISTING NUT AND WRENCH COMBINATION

Leonard J. Golan, Buffalo, N. Y., assignor to Emil V. Lapczenski, Buffalo, N. Y.

Application March 12, 1942, Serial No. 434,325

1. Claim. (Cl. 81—121)

This invention relates to combination wrench and nut sets, and particularly to those where the nuts are to be theft resistant.

There are many places where devices are secured in place by machine screws, bolts or nuts, and it has been impractical to provide locks to prevent unauthorized removal of the nuts, bolts or screws and thus to prevent theft of articles secured in position by such screws, nuts or bolts.

An object of the invention is to provide an improved theft resisting nut and wrench set which may be easily manufactured, and sold at a cost which will make it easily marketable.

Another object of this invention is to provide an improved nut and wrench combination, with which removal of the nuts by unauthorized individuals will be made very difficult; which will reasonably protect a device against theft through unauthorized removal of nuts, screws, or bolts by ordinary thieves; which may be used where the heads of the bolts or screws or the nuts are disposed in close proximity to a wall which interferes with the free application thereto of a pipe wrench or other type of wrench; with which any nut, screw or bolt may be removed only by use of a special wrench; with which a very large number of different combinations of nuts and special interfitting nuts and wrenches may be obtained; and which will be relatively simple, practical and inexpensive.

Other objects and advantages will be apparent from the following description of several embodiments of the invention, and the novel features will be particularly pointed out hereinafter in connection with the appended claim.

In the accompanying drawing:

Fig. 1 is an elevation of a nut and wrench combination constructed in accordance with this invention, and illustrating one embodiment of the same, but with the nut and wrench separated and disposed in position to be coupled;

Fig. 2 is a transverse sectional elevation through the nut, the section being taken approximately along the line 2—2, Fig. 3.

Fig. 3 is an end elevation of the nut of the same;

Fig. 4 is a longitudinal, sectional elevation through the wrench part of the combination, the section being taken approximately along the line 4—4, Fig. 5;

Fig. 5 is an end elevation of the wrench of Fig. 4;

Fig. 6 is a transverse sectional elevation through the wrench, the section being taken approximately along the line 6—6 of Fig. 4;

Fig. 7 is a longitudinal sectional elevation similar to Fig. 4, but illustrating a slight modification thereof, the section being taken approximately along the line 7—7, Fig. 8;

Fig. 8 is a transverse sectional elevation through the embodiment of Fig. 7;

Fig. 9 is a perspective of one of the keys employed in the embodiment of Figs. 7 and 8;

Fig. 10 is a transverse sectional elevation 10 through the wrench and nut when they are coupled, the wrench and nut being made in accordance with the embodiment of the invention shown in Figs. 1 to 6;

Fig. 11 is a transverse sectional elevation 15 through a wrench also constructed in accordance with this invention, but illustrating another arrangement of the interlocking portions;

Fig. 12 is an end or face elevation of a nut for which the wrench of Fig. 11 is designed;

Fig. 13 is a transverse sectional elevation 20 through another wrench also constructed in accordance with the invention but illustrating still another arrangement of the interlocking features;

Fig. 14 is an end elevation of a nut designed to 25 receive the wrench of Fig. 13;

Fig. 15 is a transverse sectional elevation 30 through another wrench also constructed in accordance with this invention but illustrating still another arrangement of the interlocking features;

Fig. 16 is an end elevation of a nut designed to receive the wrench of Fig. 15;

Fig. 17 is an end elevation of a wrench constructed in accordance with this invention, but 35 having an integral operating handle;

Fig. 18 is a side elevation, partly in section, of 40 a wrench also constructed in accordance with this invention, but illustrating a slightly different manner by which the socket may be turned;

Fig. 19 represents in end elevation a group of 45 different keys that may be used in order to vary the possible combinations of wrenches and nuts; and

Fig. 20 is an end elevation of a nut to which 50 a wrench having one or more of the keys of Fig. 19 may be applied.

In the embodiment of the invention illustrated in Figs. 1 to 6, a nut 1, the removal of which by 55 unauthorized persons or thieves is to be prevented, is threaded upon the end of a bolt or stud 2 passing through an object 3 and terminating in a recess 4 in which the nut 1 is disposed. The wrench 5 is the tubular socket type of wrench, and of a size to enter the recess 4 and telescope

slidely over the nut 1. The wrench 5 at its opposite end is suitably formed to enable it to be turned, and for this purpose, it may for example, have a hexagonal-shaped end projection 6 to receive an ordinary wrench by which turning torque may be applied to the socket wrench 5. The nut 1 shown in the drawing is generally cylindrical in periphery, that is, it is provided with a generally smooth, approximately circular periphery, so that the ordinary wrench cannot be applied thereto and exert any turning torque thereon. The nut has one or more keyways or grooves 7 cut into its periphery and extending from one end or face thereof a substantial distance toward the opposite end, and preferably entirely from end to end.

These grooves or keyways 7 are non-symmetrically or unequally spaced around the periphery of the nut, and they have substantial surface areas 8 between the grooves. The wrench 5 includes a body or element 9 of any suitable material, usually strong metal, which is provided with a chamber or recess 10 extending inwardly a substantial distance from one end. The recess 10 is of a size and shape to fit over the nut 1 by sliding, telescopic action thereon. The body 9 is provided with any desired number of milled slots 11, which extend entirely through the peripheral wall around the socket for a substantial distance from the open end of the recess 10, and terminate at their inner ends in oblique end walls 12. These end walls 12 are outwardly facing for a substantial part of their length, for a purpose which will appear presently. Disposed in each slot 11 is a key or rib 13 which has a greater width than the thickness of the wall of the body or element 9 around the recess 10, so that each rib or keyway will fill the slot and also project a short distance into the recess 10 of the body or element 9 and provide a key in that recess extending in an endwise direction from the open end of the recess.

Each key or rib is provided with a beveled end 14 or other inwardly facing portion to overlap the outwardly facing portion of the end wall 11 of the slot. The engagement between the walls 12 and 14 will limit the movement of the inner end of the rib or key 13 towards the center of the recess 10. A shell or casing 15 encircles the body or element 9, so as to close the outer edges of the slots 11, and by engagement with the outer edges of the ribs or keys 14, limit any outward movement of the keys in a radial direction.

One end of the shell 15 is flanged over as at 16, so as to engage the end of the body or element 9 which is opposite from the end having the recess 10. The other end of the shell 15, at the open end of the recess, is flanged toward the axis of the recess as at 17, so as to overhang the end of the body or element 9 and thus prevent endwise displacement of the shell 15 on the body or element 9. The flange 17 is further turned angularly to extend toward element 9 and provide an annular flange 18 which enters an annular groove 19 in that end of the body 9 having the recess 10, and the keys 13 at their outer ends also have slots 20 into which the flange 18 extends. The flange 18, by its engagement in the slots 20 in the outer ends of the keys, prevents inward movement of the outer ends of these keys. Thus the keys are effectively confined in the slots in the element or body 9 and serve as longitudinally extending ribs or key portions extending as interval ribs or keys into the recess 10.

These ribs 13 are arranged or spaced from one

another about the peripheral wall of the recess 10 to correspond to the arrangement and spacing of the grooves 7 in the nut 1, and the keys 13 are slightly thinner than the widths of the grooves 7, so that when the socket wrench 5 is moved endwise in telescoping relation with the nut 1, and the wrench 5 is turned to bring the keys or ribs 13 into alignment with the grooves 7 of the unit, the wrench 5 may slidingly telescope over the nut 1 and be coupled thereto. During this telescoping movement, the ribs 13 enter and slide along the grooves 7 like keys in keyways, and thus provide an effective means for transferring turning torque between the wrench 5 and the nut 1. By applying a suitable turning implement to the hexagonal end 6 of the socket wrench 5, one may turn the nut 1 in either direction, either to tighten it or loosen it.

It will be observed that unless the wrench has a spacing of the ribs 13 corresponding to the spacing of the grooves 7, it is impossible to apply the wrench to the nut, and thus one must possess a particular type of wrench in order to turn the nut 1. By varying the spacing of the grooves 7 and a corresponding spacing of the ribs or keys 13, and by varying the thickness of the ribs and widths of the grooves, a large number of different combinations of complementary surfaces for the nut periphery and the recess periphery may be obtained.

In Figs. 7, 8 and 9, the arrangement is similar to that in Figs. 1 to 6, except that the slots 21, which correspond to the slots 11, do not need the outwardly facing end wall but may have a mere vertical end wall 22, and the key 23, instead of being a flat metal strip, is of T-shape in transverse cross section, as shown in Figs. 8 and 9, with the stem of the T extending through the slot 21 into the recess 22 corresponding to the recess 10. The slot 21 along the outer surface or periphery of the body 9 is widened or countersunk as at 24, to receive the head of the T flush with the wall of the body around the recess, as shown in Fig. 8. The head of the T limits the movement of the key through the slot 21 into the recess 22. The shell 25, which corresponds to the shell 15 of Fig. 4, is a mere encircling shell with its ends 26 and 27 flanged over the ends of the body 9 so as to prevent displacement of the shell on the body 9 and to overhang the ends of the keys or ribs 23 and prevent their endwise movement along the slots 21. This type of wrench may be applied to the same type of nut as disclosed in Figs. 1 to 6.

In Figs. 1 to 10, I have for convenience, illustrated the grooves as formed entirely in the nut, and the ribs as carried entirely in the wrench, because of the ease of cutting the grooves and slots, but it will also be understood that the ribs may be provided entirely on the nut 1, and the grooves in the peripheral wall of the recess 10 or 22, so as to provide the turning torque between them. I may also provide ribs and grooves in both the nut and the socket in order to increase the number of possible combinations and permutations of parts, and give a larger variety of patterns for the nuts and wrenches, and thereby increase the number of safety combinations available.

In Figs. 11 to 16, I have illustrated several of such different combinations and arrangements of the grooves and ribs to provide different patterns. For example, in Fig. 12, the nut 28 is provided with a plurality of ribs 29 and a plurality of grooves 30, both of which extend in

a direction endwise of the nut from one end face thereof, which would be the outer end face of the nut when the nut is applied to a stud or bolt. In Fig. 11 the wrench 31 is provided with grooves 32 in its internal periphery defining the recess 33, which grooves are of a size and spacing to receive the ribs 29 on the periphery of the nut 28 of Fig. 12. The wrench 31 is also provided with keys or ribs 34 which are of a size and spacing around recess 33, to enter and slide along the grooves 30 in the periphery of the nut 28. Obviously any different arrangement of ribs and grooves in the wrench 31 would not fit the nut of Fig. 12, and hence the wrench could not then be telescoped over that nut.

Similarly in Figs. 13 and 14 the socket wrench and nut are respectively similar to those in Figs. 11 and 12, except for the different arrangement of the ribs and grooves to show particularly how the combination may be varied.

In Figs. 15 and 16 are illustrations of a socket wrench and nut respectively which represent further changes in the arrangement of ribs and grooves, and also showing the use therein of the T-shaped ribs 23 of Figs. 7 to 9, as well as the plain flat ribs 11 of Figs. 1 to 6.

In Fig. 17, I have illustrated a socket wrench 35 having a recess 36, with any desired spacing of the ribs 37 and grooves 38 to fit a particularly designed nut periphery, and in this instance, the socket wrench is provided with an integral handle 39 by which the socket wrench 35 may be turned.

In Fig. 18, the wrench 40 is formed as in any of the embodiments of Figs. 1 to 16, but instead of having the hexagonal end projection 6 as in Figs. 1 to 7, the same end of the body 9 is provided with a square passage or recess 41 which receives the end of a turning implement 42 of square cross section. This implement 42, whether straight or angular, serves as a handle by which the wrench or socket 40 may be turned.

In Fig. 19, I have illustrated a group of keys 23a which are similar to the keys 23 except that their inner ends have different edge forms or configurations 43. A nut 44 with which such keys may be used, is shown in Fig. 20, and in that nut the bottom walls 45 of the grooves 46 in which such ribs are received, have forms or configurations that are complementary to the forms 43, so that ribs of the kind shown in Fig. 19 can enter only those grooves which have the proper configuration of the bottom wall to receive the particular complementary shapes of the free edges of the ribs. Obviously the free edges of the ribs 23a may be given any other changes in shape, form or configuration in order to further increase the possible combinations of details by which each nut can receive only a particular wrench designed for it, thereby making it impossible for the average person or thief to remove any nut without first possessing the proper wrench designed for the nut.

In the use of the word "nut" throughout the specification and claims, it is to be understood that any anchorage part or member which is to be turned to apply or remove it, whether it is the head of a bolt or screw, or a nut, and which may be turned by application of a wrench thereto, is to be considered as the equivalent of the word "nut" in interpreting these claims, and in understanding the invention. An example of the use of such nuts and wrenches is in securing the removable wheels of automobiles to hubs in order to prevent the theft of tires. The only change necessary to apply this invention to present-day automobiles is merely to replace one or more of the ordinary hexagonal-shaped nuts used on each wheel with nuts formed in accordance with this invention. The special nuts provided for each automobile may be all of the same pattern, so that one wrench will serve for all of the nuts on the same car. These nuts which secure the removable wheels to the hubs on automobiles are usually disposed close to a side wall of the central recess in which they are placed which makes the use of a socket wrench very desirable and almost necessary. A socket wrench such as shown in the drawing can be easily applied to nuts close to a side wall such as wall 45 in Fig. 1, and the wrench part 5 may be long enough to extend out of the hub or recess where an ordinary wrench can be applied over the hexagonal end projection 6, or a special wrench such as 42 applied to recess 41.

It will be understood that various changes in the details and arrangements of parts, which have been herein described and illustrated in order to explain the nature of the invention, may be made by those skilled in the art within the principle and scope of the invention as expressed in the appended claim.

I claim:

40 A socket wrench comprising a body having a recess opening inwardly from one end thereof, and having a slot extending from said end in a direction endwise of said body, terminating in an outwardly facing end wall, a key disposed in and filling said slot, projecting into said opening and having an end portion overhanging said outwardly facing end wall to limit its movement in said slot into said recess, a shell encircling said body and preventing radially outward movement of said key in said slot, the end of said shell at the open end of said slot being flanged over the end of said body and slot to prevent endwise movement of said key lengthwise of said slot, and also flanged toward the adjacent end of said body, said key having a slot in its end wall to receive said last named flange which prevents inward movement of the outer end of said key.

LEONARD J. GOLAN.
